(57) **CLAIM**

The ornamental design for a front panel, as shown and described.

DESCRIPTION

FIG. 1 is a perspective environmental view of the front panel, as seen from above and to the right;

FIG. 2 is a front view of the front panel;

FIG. 3 is a left view of the front panel;

FIG. 4 is a right view of the front panel;

FIG. 5 is a bottom view of the front panel; and,

FIG. 6 is a top view of the front panel.

The broken line showing of an equipment housing is for illustrative purposes only and forms no part of the claimed design.
